ENVELOPES

SUMMARY OF THE INVENTION

This invention is concerned with an envelope made from a blank of paper which may be opened by automatic mail opener without damaging the contents. The envelope is provided with a projecting portion which is separated from the contents and may be slit to open the envelope without damaging the contents.

An object of this invention is an envelope that may be opened by an automatic mail opener and in which the contents of the envelope are protected against damage by the cutting edge of the mail opener.

Another object is an envelope which may be safely opened by an automatic mail opener even though it is stuffed full.

Another object is an envelope which facilitates rapid opening of mail.

Another object is an envelope of the nature described which may be formed from a blank of paper.

Another object is an envelope designed for opening by an automatic mail machine but which may be opened in a conventional manner if no automatic mail opening machine is available.

Other objects may be found in the following specification, claims and drawings.

BRIEF DESCRIPTION OF THE DRAWINGS

The invention is illustrated more or less diagrammatically in the following drawings wherein:

FIG. 1 is a plan view of the back or rear of the envelope in its assembled and sealed condition;

FIG. 2 is a partial cross-sectional view taken along lines 2-2 of FIG. 1;

FIG. 3 is a view similar to FIG. 2 showing the envelope after an automatic mail opener has made a cut therein;

FIG. 4 is a view similar to FIG. 2 showing the envelope in an opened position; and

FIG. 5 is a top plan view of a blank for making the envelope of FIG. 1;

DESCRIPTION OF THE PREFERRED EMBODIMENT

FIG. 1 shows an envelope 11 made in accordance with the teachings of this invention. The envelope is made from the blank 13 shown in FIG. 5 and when used holds contents such as the sheet 15 shown in FIG. 2.

The blank 13 (FIG. 5) is preferably a single sheet of paper having a generally rectangular portion 17 which forms the front or face of the envelope. Formed integrally with the rectangular portion 17 are a sealing flap 19, side flaps 21 and 23 and a bottom flap 25. When folded, the bottom flap cooperates with the side flaps 21 and 23 in the manner shown in FIG. 1 to form the rear wall or back 27 of the envelope. The sealing flap 19 and side flaps 21 and 23 are connected to the rectangular portion 17 along fold lines 31, 33 and 35 respectively.

The bottom flap 25 is connected to the rectangular portion 17 by four side-by-side strips 41, 43, 45 and 47. Strip 41 connects to rectangular portion 17 along fold line 51. It connects to strip 43 along fold line 53. Strip 43 connects to strip 45 along fold line 55. Strip 45 connects to strip 47 along fold line 57. Strip 47 connects to the bottom flap 25 along fold line 59.

Strips 41 and 47 are of the same width and each is covered on the side shown in FIG. 5 with adhesive 61 and 63, respectively. The adhesive is preferably a moisture and pressure actuated glue of the type commonly used on envelopes. Strips 43 and 45 are also of the same width but are wider than strips 41 and 47.

Adhesive, also preferably a moisture and pressure actuated glue, is placed in strips or bands 65, 67 and 69 on the sealing and side flaps 19, 21 and 23. It should be noted that the adhesive on the flaps is applied to the opposite side of the blank 17 to which the adhesive 61, 63 is applied.

The use, operation and function of this invention are as follows:

The blank 13 is assembled into an envelope 11 by folding the bottom flap 25 about the fold line 55 and against the underside of the rectangular portion 17 of the blank as viewed in FIG. 5. This positions the strip 47 next to the strip 41 and the strip 45 next to the strip 43. The strips are then folded about the fold lines 57, 53 which are in alignment, to form a pleat in which the strips 43, 45 are in contact with each other and the strips 41, 47 are in contact with each other. The folded strips of the pleat are then folded over the bottom flap 25 in a manner in which the strip 47 and its adhesive 63 engage the bottom flap 25 and the strip 43 engages the adhesive 61 on the strip 41 in the manner shown in FIG. 2. With the strips folded in this manner, a portion of the strips 43, 45 along their connecting fold line 55 will extend beyond the periphery of the folded envelope in the manner shown in FIG. 2. The side flaps 21, 23 are then folded to overlie the bottom flap 25 and their adhesive 67, 69 connects these flaps to the bottom flap 25 to form the envelope 11.

When contents, such as a paper 15, is placed in the envelope 11, it will seat short of the fold lines 51, 59 due to the doubled flap formed at the end of the envelope. When the envelope is put in an automatic letter opener machine, a cut is made through the strips 43, 45 along line 73 as shown in FIG. 3 to separate a portion 75 from these strips. This permits removal of the strips 41 and 43 which are fastened together by the glue 61 thereby permitting entrance to the envelope to remove the paper 15 as shown in FIG. 4.

Whereas, the preferred form of the invention has been shown and described it should be understood that there are many modifications, alterations and changes which may be made without departing from the teachings of the invention. Therefore, the scope of the invention should be only limited by the claims attached hereto.

I claim:

1. An envelope of generally rectangular shape formed from a sheet of paper, said sheet of paper including a generally rectangular portion forming the front wall or face of the envelope, a sealing flap, side flaps and a bottom flap attached to the edges of said rectangular portion, said side flaps and bottom flap forming the rear wall or back of the envelope, four side-by-side strips joining said bottom flap to said front wall and separated by fold lines, the strips adjoining the bottom flap and front wall being equal in width, and the remaining two strips being equal in width but wider than said strips adjoining said bottom flap and front wall,

said envelope being formed by folding said bottom flap and said side flaps over said rectangular portion with said strips being folded and reversely folded to form a pleat having inner and outer portions along the bottom edge of the envelope,
 said inner portion of said pleat being formed of the strips adjoining the bottom flap and front wall,
 said outer portion of said pleat being formed of the middle strips with said outer portion of said pleat extending beyond the periphery of the bottom 10 edge of the envelope,
 said inner portion of said pleat being secured to said envelope by adhesive connecting said bottom flap and said strip adjoining said bottom flap,
 said outer portion of said pleat being held to said 15 inner portion of said pleat by adhesive connecting said strips adjoining said front wall and said middle strip located next to said strip adjoining said front wall.

2. A blank for forming an envelope of the type which 20

may be opened by an automatic letter opener without damaging the contents contained therein, said blank including:
 a generally rectangular portion forming the front wall or face of the envelope, a sealing flap, side flaps and a bottom flap each attached to the edges of said rectangular portion by fold lines,
 four side by side strips joining said bottom flap to said rectangular portion with said strips separated by fold lines,
 the strips adjoining the bottom flap and the rectangular portion being equal in width and covered on one side with an adhesive,
 the middle strips being equal in width but wider than said strips adjacent said bottom flap and front wall, adhesive formed on said sealing flap and said side flap on the opposite side of said blank from the side having adhesive on said adjacent strips.
